ANTIDETONATING DEVICE

Stanley M. Udale, Detroit, Mich., assignor to
George M. Holley and Earl Holley

Application October 13, 1945, Serial No. 622,133

2 Claims. (Cl. 261—18)

1

The object of this invention is to reduce the knocking of an airplane engine.

The use of an anti-detonating fuel to be used during wide-open throttle is a well-known method of operating an engine.

The drawing shows diagrammatically the preferred form of my invention.

In the drawing, 10 is the air entrance leading to the carburetor of the variable-venturi type, two throttles 12 and 14 are geared together by two gears 20 and 22. A smaller gear 24, operated by an operating throttle lever 26, is used to vary the area of the air stream.

A cam 30, mounted on the shaft of the lever 26, engages with the lever 28, which lever 28 moves the needle 32 by means of a tension spring 80, which holds the roller 75 in engagement with the cam 30, so that the needle 32 is opened as the throttles 12 and 14 are opened by the lever 26. Openings 16 and 18 are provided for the venting of the throttles 12 and 14, so that the throttles 12 and 14 are more or less aerodynamically balanced and the effort to move them is not too great. Fuel enters through a fuel venturi 46, flows down a pipe 44, passes an inlet needle 64 and a corresponding inlet needle 66. These inlet needles 64 and 66 are connected to links 96 and 78. The links 96 and 78 are connected to diaphragms 68 and 70 in a well-known manner. The atmospheric pressure is admitted to the chambers 72 and 74 through the air vent 82 and the cross-passage 84.

Fuel leaves the fuel chamber 42 through the passage 34 and flows by the needle 32 and flows down the passage 36, which passage is vented at 88 to the air entrance 10. The fuel that flows down the passage 36 discharges into the throat of the variable venturi formed by the throttles 12 and 14 in a well-known manner and this carburetor is no part of this invention.

The anti-detonating fluid is admitted through a pipe 90, which enters the passage 92. This anti-detonating fluid discharges through the openings 38 and 40 into the throat of the variable venturi 12—14. The anti-detonating fluid is contained in a tank 60, but the pressure for the tank 60 is derived from the pressure of the fuel flowing to the venturi 46. A passage 50 is connected to a chamber 52, and the chamber 52 is connected through a passage 62 to the upper portion of the tank 60. Hence, whatever pressure there may be supplying fuel to the pipe 44 through the venturi 46, that pressure is available for the upper part of the tank 60. The lower part of the tank 60 contains alcohol or other anti-detonating fluid. The fuel in the upper part of tank 60 will ultimately become gasoline, as the anti-detonating

2

fluid is pushed out of the lower part of the tank 60, up through the passage 58, past the needle 56, into the passage 90. A passage 48 connects the throat of the venturi 46 with a chamber 98, which contains a compression spring 76. The chamber 98 is bounded on its right-hand side by the diaphragm 54. The chamber 52, as stated above, is subjected to the full pressure of the gasoline entering the venturi 46, and it is bounded on its right-hand side by the diaphragm 54. Hence, the diaphragm 54 is responsive to the pressure drop due to the fuel flow through the venturi 46. Hence, at high fuel flows, the needle 46 opens and admits anti-detonating fluid from the tank 60, but it is only at high air and fuel flows that anti-detonating fluid is needed.

Operation

In the normal operation of the carburetor, the 20 needle 56 is closed by the pressure exerted by the spring 76 and the carburetor functions in the ordinary way, that is, the throttles 12 and 14 are opened and gasoline is taken from the fuel chamber 42 and is discharged into the throat of the 25 variable venturi 12—14. When critical fuel and air flows are reached, the diaphragm 54 moves to the left, the spring 76 is compressed, the needle 56 is opened, fuel flows down the passage 90 into the cross-passage 92 and out of the openings 38—40. Hence, the quantity of anti-detonating fuel supplied depends on the amount of gasoline flowing through the venturi 46, but no anti-detonating fluid is supplied until the quantity of gasoline flowing through the venturi 46 exceeds 35 a predetermined critical value.

What I claim is:

1. In a carburetor having a main fuel entrance, means for adding anti-detonating fuel, a source of ordinary fuel under pressure, a fuel venturi 40 connected thereto in the main fuel entrance to said carburetor, a fuel tank containing anti-detonating fuel, a passage connecting the top of the anti-detonating tank to said ordinary fuel pressure line, an outlet from the bottom of said 45 anti-detonating fuel tank, a passage connecting said outlet with the carburetor, a valve for controlling the flow through said passage, a moving wall responsive to the drop of pressure in said fuel venturi, mechanical means connecting said 50 moving wall with said valve whereby said valve opens whenever the flow of the ordinary fuel exceeded a predetermined critical value.

2. In a carburetor having a main fuel entrance, means for adding anti-detonating fuel, a source 55 of ordinary fuel under pressure, a fuel restriction connected thereto in the main fuel entrance to said carburetor, a fuel tank containing anti-

detonating fluid, a passage connecting the top of the anti-detonating fluid tank to said ordinary fuel pressure line, an outlet from the bottom of said anti-detonating fluid tank, a passage connecting said outlet with the carburetor, a valve 5 for controlling the flow of anti-detonating fluid through said passage, a moving wall responsive to the drop of pressure through said fuel restriction, mechanical means connecting said moving wall with said valve whereby said valve opens whenever the flow of the ordinary fuel exceeded a predetermined critical value.
